UNITED STATES PATENT OFFICE.

CARL SODERLUND, OF AKRON, OHIO.

DESIGN FOR A CUSHION-TIRE TREAD.

59,134.

Specification for Design.

Patented Sept. 20, 1921.

Application filed May 7, 1921. Serial No. 467,579. Term of patent 14 years.

To all whom it may concern:

Be it known that I, CARL SODERLUND, a citizen of the United States, residing at Akron, in the county of Summit and State of Ohio, have invented a new, original and ornamental Design for Cushion-Tire Treads, of which the following is a specification, reference being had to the accompanying drawing, forming part thereof.

The figure is a plan view of a cushion-tire tread, showing my new design.

I claim:

The ornamental design for a cushion-tire tread, as shown.

CARL SODERLUND.
